UNITED STATES PATENT OFFICE.

LEWIS FERRY MOODY, OF PHILADELPHIA, PENNSYLVANIA.

HYDRAULIC DRAFT TUBE.

Application filed November 28, 1922. Serial No. 603,769.

This invention relates to hydraulic turbines and in particular to an improved means for receiving water from the turbine runner and delivering it to the tail race. More particularly my invention relates to means of this character wherein the water is turned or spread out from a direction along the axis of the runner into diverging radial directions and is subsequently turned into a single radial direction for discharge into the tail race.

In many modern hydraulic power plants the turbines are placed in a row with vertical shafts, the water entering the turbines on one side of the row from the penstocks or forebay and discharging at the other side into the tail race. The water leaves the runners in a downward direction at high velocity and some means should be provided which will reduce this velocity so as to correspondingly reduce the back pressure on the turbine runners and which will likewise turn the flow into a horizontal down stream direction. This means should be constructed so as to perform these functions without appreciable losses of energy and should itself occupy a minimum space. The last condition is particularly desirable in order that the turbines themselves may be closely spaced and the power house dimensions made as small as possible.

For the purpose of reducing the velocity, draft tubes have been used which direct the flow from the runner radially outward on spreading lines and discharge it horizontally in every direction. The flow may then be received by a collector which turns it into a common down-stream direction. Certain portions of the flow must be turned through substantially 180° while other portions, which leave the tube in a direction more nearly approaching the down-stream do not have to be turned through so great an angle.

If an unlimited space were available the initial velocity with which the water enters the draft tube could be reduced and its kinetic energy turned into effective head for the turbine by the use of the spreading action alone, that is, the water could be discharged outwardly in all directions at such a low velocity that but little kinetic energy would remain in it. The problem of collecting the flow and discharging it down-stream would be solved by the use of any suitable collector which would not cause an appreciable loss of head.

With the available space limited, however, it is desirable to provide a draft tube of such dimensions that the water discharged into the collector will retain a portion of its kinetic energy and that the collector be so designed as to reduce further the velocity of the water and to regain this energy. The water leaving the draft tube in an up-stream direction may be conveniently collected from the tube by one or more spiral passages extending circumferentially around the cylindrical outlet of the tube and discharging tangentially down stream toward the tail race. These spiral passages should be enlarged at a rate greater than is necessary to accommodate the cumulative flow so that the velocity of the flow therethrough will be gradually reduced.

One of the objects of the present invention is to provide an improved collector of this character which is designed to receive a flow of considerable velocity from the draft tube and is adapted gradually and uniformly to reduce the velocity of this flow and so regain its kinetic energy.

Another object of my invention is to provide in addition to the spiral collector passages above described an effective means for decelerating that portion of the flow which does not enter the spiral passages.

Numerous other objects and advantages will appear from the following description taken in connection with the accompanying drawings which illustrate certain of the preferred embodiments of my invention and wherein—

Fig. 1 is a view showing vertical sections of a draft tube and collector taken on the line 1—1 of Fig. 2 looking in the direction of the arrows.

Fig. 2 is a view showing a horizontal section on the line 2—2 of Fig. 1.

Fig. 3 is a view similar to Fig. 1 but showing a slightly modified construction.

Fig. 4 is a view showing a vertical section, 100 on the line 4—4 of Fig. 5, of a still further modified form of my invention.

Fig. 5 shows a horizontal section taken on line 5—5 of Fig. 4.

Fig. 6 a vertical section on the line 6—6 105 of Fig. 5.

Fig. 7 which is a sectional view on line 7—7 of Fig. 8 shows a still further modification.

Fig. 8 is a horizontal sectional view on the line 8—8 of Fig. 7.

Fig. 9 shows a vertical sectional view on the line 9—9 of Fig. 8.

Fig. 10 shows a vertical section taken on the line 10—10 of Fig. 8 looking in the direction of the arrows.

Fig. 11 shows in vertical section on the line 11—11 of Fig. 12 a further modification.

Fig. 12 a horizontal section on the line 12—12 of Fig. 11.

Fig. 13 a vertical section on the line 13—13 of Fig. 12.

Fig. 14 a vertical section on the line 14—14 of Fig. 12 taken in the direction of the arrows.

Fig. 15 represents a vertical section on line 15—15 of Fig. 16 and shows a modification in the form and arrangement of the collector passage and

Fig. 16 shows a section on line 16—16 of Fig. 15.

Referring to Figs. 1 and 2 reference character 20 indicates generally the primary draft tube and 21 the collector. The primary draft tube as shown is formed of an outer wall 22 having a slightly tapered or conical upper portion 23 and gradually curved outward to a horizontal direction at its lower end. Projecting upwardly from the floor 25 of the collector passage into the flaring end of the wall 22 and concentric therewith is a cone 26 whose concave surface is formed in relation to the outline of the flared end of the wall 22. The outer wall 22 and cone 26 together form the primary draft tube which serves to direct the flow downward from the turbine runner and outwardly into a horizontal plane. The cross sectional area of this tube as shown increases gradually so as to give a gradual deceleration to the meridian components of the flow, and at the same time the tube is adapted to handle efficiently flow containing whirling components about the turbine axis.

The outer wall of the tube is cut away to form the collector passage 21, the material around the outer wall of the tube thus forming a projection 28, depending into the collector chamber. The general contour of the bottom of this projection is shown in Fig. 2 by the line 29. This projection joins the side wall 30 of the collector passage at a point 31 farthest removed from the tail water and is formed with a vertical side wall joining its bottom with the upper wall 33 of the collector chamber at a point 32 nearest the tail water. Between these two diametrically opposite points the side wall of the projection 28 slopes inwardly a horizontal distance represented by the distance between the lines 29 and 35 in Fig. 2, thus forming a channel 36 which lies above or overhangs the flared portion of the draft tube. The outer side wall 30 of the collector chamber recedes from the projection 28 so as to provide a passage of constantly increasing area which will take care of the cumulative flow and also continuously reduce the velocity. By reason of the over-

hanging portion of the collector chamber the outer wall of the chamber may be placed nearer the axis of the tube and thus the economy of space be secured.

It will be noted that the water flowing out of the draft tube in the general down-stream direction does not pass upward into the overhanging channel 36 but flows for a certain distance between two flat surfaces formed by the floor 25 and the bottom of the projection 28. In so flowing it diffuses and is spread laterally in a general direction indicated by lines 40' and 41' of Fig. 2. Water flowing laterally and water which flows in an upstream direction from the draft tube will turn upwardly to fill the passage 36. The lateral and upstream flows merge within passage 36 and flow in a downstream direction therein. The flow in the passage 36 when reaching the downstream edge of member 28 (see Fig. 2) merges with the downstream flow disposed between the bottom 25 and the opposed surface of projection 28. There is thus provided, in effect, a separate passage for the water leaving the draft tube in the down-stream direction and one which permits the flow to increase in area and consequently to decrease in velocity.

If the rapidly moving water which is being discharged from the draft tube in a downstream direction which I will term the "direct flow" were permitted to discharge directly into tail water or other wide open space, that is, a space which does not provide for its gradual diffusion, the kinetic energy of the flow would be lost. Furthermore if the direct flow were permitted to mix with the slower moving water from the other portions of the draft tube eddies and cross-currents would be created which would cause a further loss of energy.

In the form shown in Figs. 1 and 2 the upper and lower surfaces between which the direct flow proceeds are parallel, while in Fig. 3 I have inclined the upper surface 43 upwardly toward tail water by a small angle α so as to give a greater reduction in velocity. The angle between the upper and lower surfaces should not exceed approximately 15° or in extreme cases 20° , if an efficient velocity conversion is to be secured.

In the form of my invention shown in Figs. 4 to 6 I have maintained the outer wall of the projection 28 vertical or substantially vertical and so there is no overhanging channel 36 as shown in the prior figures. The upper wall of the collector chamber is curved upwardly as is indicated at 44 in Fig. 6 to provide the necessary increase in area. The lower end of the projection 28 in these figures has a different contour from that shown in Fig. 2 as may be readily seen. In Fig. 5 the projection extends much further down-stream and is joined at its extended end to the floor of the discharge passage by means of a pier or par-

tion 45. This partition is of such a form and is located at such a distance from the discharge end of the tube as not to interfere with the "direct" flow toward the tail water.

5 The structure shown in Figs. 4 to 6 is less expensive to build than that shown in the previous figures and may be employed when somewhat more space is available.

The curved collector passages shown in Figs. 1 to 6 are of the double spiral type and are intended to be employed where the water is discharged from the draft tube with only small degrees of whirl, that is, such a structure is intended to be used with turbines of 15 moderate or low specific speeds. In the form of my invention shown in the remaining figures I have provided for the collection of a whirling discharge.

In the form shown in Figs. 7 to 10 I provide a single curved collector channel which starts at a point 40 at the mouth of the draft tube, is curved around the axis of the tube through an angle of approximately 180° and terminates in a straight passage 47 having a 25 direction downstream and substantially tangential to the draft tube. The inner and outer walls of this passage are vertical and its upper and lower walls horizontal except that the upper wall of the outer passage is inclined upward at an angle preferably not to exceed about 15°.

The passage 49 for discharging the direct flow is substantially rectangular in cross-section and is formed by the floor 25, top wall 50 35 which is inclined upwardly at an angle not to exceed about 20°, side wall 51 and wall 52, the last being formed by a partition 53 which separates the passage for the direct flow from the end of the curved passage.

40 It will be noted that the draft tubes as shown in Figs. 7 and 9 are much shorter than those shown in the previous figures and do not have the intermediate straight conical portion between the runner and the beginning of the spreading portion.

The form of my invention shown in Figs. 11 to 14 is similar to that shown in Figs. 7 to 10 except in the former the curved collector passage does not terminate in a straight section but continues to curve so that the total curve exceeds 180° and also continues to flare horizontally through its entire course. This passage is quite narrow but considerably higher than those shown in previous figures.

55 The partition of Figs. 7 and 8 is omitted, there being merely a strut 56 between the upwardly extending top wall of the passage for the direct flow and the floor 25. The cone shown in this form of my invention extends 60 upwardly through the entire draft tube to the runner and the runner shown is of the propeller type. If desired the form shown in these figures may have the over-hanging passage collector shown in Fig. 1.

65 In Figs. 15 and 16 I have shown a modi-

fied construction and arrangement of collector for use where lateral space is limited. The collector passage here shown surrounds the outlet of the draft tube and extends downwardly therefrom and under the cone 60. 70 The form of the inner wall of the expanding collector passage beneath the cone is indicated by the line 61 beginning at the point 62 where this wall joins the outer wall 63 and ending at 64 at the outlet 65.

75

While I have shown a primary draft tube which is constructed to progressively increase in area in certain cases it may be necessary to employ one whose principal function is to turn the water outwardly in all directions 80 without being able to produce any substantial decrease in velocity. With the use of such tubes it would be necessary to employ a collector which will reduce the velocity of the flow from an amount which is only slightly 85 less than its velocity at the runner.

Moreover even with these turbines where in the discharge velocity from the spreading conduit is sufficiently small to be so thrown away when the turbine is operating at its 90 normal capacity, it must be considered that under the usual conditions turbines are frequently called upon to operate at capacities considerably above normal and when so operating the discharge velocity from the 95 spreading conduit rapidly increases and may represent a very material amount of velocity head in comparison with the available head on the plant. A failure to provide for efficient deceleration of this velocity of discharge from the spreading or primary draft tube may therefore materially restrict the full-load capacity of the turbine even in cases where the primary or spreading conduit is sufficient in itself to take care of the ordinary and normal load conditions with high 100 efficiency. The proper formation of the collector passages therefore may have a vital effect upon the full power capacity of the turbine.

105

110 It should also be considered that by providing efficient collector passages the size of the primary portion of the draft tube may be cut down without serious loss of draft tube efficiency, but with a material reduction in 115 the over-all dimensions of the entire draft tube, and consequently of the power-house and sub-structure.

120 While I have shown my invention as applied to turbines having vertical axes it is obvious that with slight modification of structure my invention is likewise applicable to turbines having horizontal shafts. I have also shown a draft tube and collector which receive water in an axial direction and discharge it in a radial or tangential direction, that is, along a plane at substantially right angles to the axis of the draft tube. It is of course apparent that the angle between the 125 axis and the discharge direction need not be 130

exactly a right angle as conditions of practice might make it desirable to increase or decrease this angle somewhat.

While in the foregoing description I have distinguished between the primary draft tube and the collector, it will be recognized that in other forms of my invention the primary draft tube and collector function may be so merged that no one portion of the structure 10 may be termed a primary draft tube and the remainder a collector. Such cases may nevertheless fall clearly within the scope of the present invention as set forth in the appended claims.

15 By radially spreading draft tube as employed in the claims I mean a tube which discharges the flow radially outward in all or substantially all directions, it being understood of course that such flow while passing outward may also have tangential and in certain cases axial components of velocity.

I claim:

1. A draft tube for hydraulic turbines, comprising vertical and horizontal passages, 25 said vertical passage having a wall projecting into said horizontal passage and said wall having a portion elongated in a down-stream direction to form a roof extension in the horizontal passage, whereby said horizontal passage comprises a relatively deep side passage and a relatively shallow passage, the body portion of said down stream portion being so shaped as to lie entirely inside of a straight horizontal line contacting with any 35 point of a side surface of said body portion.

2. A draft tube for hydraulic turbines, comprising vertical and horizontal passages, said vertical passage having a wall projecting into said horizontal passage and said wall 40 having a portion elongated in a down stream direction to form a roof extension in the horizontal passage, whereby said horizontal passage comprises a relatively deep side passage and a relatively shallow passage, the body portion of said down stream portion being so shaped as to lie entirely inside of a straight horizontal line contacting with any point of the outlet of said vertical passage.

3. A draft tube for hydraulic turbines, comprising substantially vertical and horizontal passages, said vertical passage having 55 a wall projecting into said horizontal passage and said wall having a portion elongated in a down stream direction to form a roof extension in the horizontal passage whereby there are formed relatively deep side 60 passages and a relatively shallow central passage, the body portion of said down stream extension being so shaped as to lie entirely inside of a straight horizontal line contacting with any point of the side surfaces of said body portion.

4. A draft tube for hydraulic turbines, comprising substantially vertical and horizontal passages, said vertical passage having a wall projecting into said horizontal passage to provide an outlet for the vertical passage, said projecting wall being elongated in a down stream direction to form an offset roof, whereby said horizontal passage includes passages having upper surfaces disposed at different elevations, the body portion of said projected wall and its elongated portion being so shaped as to lie entirely inside of a straight horizontal line contacting with any point of a side surface of said body portion.

5. A draft tube for hydraulic turbines, comprising substantially vertically and horizontally extending walls forming substantially vertical and horizontal passages, said vertical wall projecting into said horizontal passage and extending up and down-stream, the dimension of said projection down-stream being greater than that up-stream, and the body portion of said projecting wall and its down-stream projection being so shaped as to lie entirely inside of a straight horizontal line contacting with any point of the side surfaces of said body portion.

6. A draft tube for hydraulic turbines, comprising substantially vertically and horizontally extending walls forming substantially vertical and horizontal passages, said vertical wall projecting into said horizontal passage and extending up and down-stream, the dimension of said projection down-stream being greater than that up-stream and the body portion of said projecting wall and its down-stream projections being so shaped as to lie entirely inside of a straight horizontal line contacting with any point of the side surfaces of said body portion, and the floor of said horizontal passage and the under surface of said down-stream extension being relatively diverged.

7. A draft tube for hydraulic turbines, comprising a horizontal passage provided with a roof and floors, and a vertical passage projecting into said horizontal passage and having a flared end the forward part of which is continued forwardly to form a longitudinal roof extension disposed at a lower elevation than that of said other roof, and said floor and roof extension being relatively diverged and the body portion of said projecting wall and its downstream projection being so shaped as to lie entirely inside of a straight horizontal line contacting with any point of the side surfaces of said body portion.

8. A draft tube for a hydraulic turbine, comprising a horizontal passage and a vertical passage having a wall projecting into said horizontal passage, the up-stream side of said wall being of generally elliptical formation while its down-stream side is wedge shaped.

9. A draft tube for a hydraulic turbine, comprising a horizontal passage and a vertical passage having a wall projecting into said horizontal passage, the up-stream side of said wall being of generally elliptical formation while its down-stream side is wedge shaped and said horizontal passage having a spiral wall extending from a point substantially adjacent the up-stream side of said vertical passage.
10. A draft tube for a hydraulic turbine, comprising a horizontal passage and a vertical passage having a wall projecting into said horizontal passage, the up-stream side of said wall being of generally elliptical formation while its down-stream side is wedge shaped, and means forming a projection extending laterally from said wall.
11. In a turbine, a draft tube having a radially spreading vertical passage provided with an outlet, and a collector passage having a spiral side wall beginning adjacent the outlet of said vertical passage and having a portion occupying space lying nearer to the axis of said vertical passage than the outlet thereof, a direct discharge portion forming a down-stream continuation of the vertical passage outlet and adapted to decelerate the flow between upper and lower surfaces, and a lateral projection extending substantially the length of said direct discharge portion.
12. In a turbine, a draft tube having a radially spreading vertical passage provided with an outlet and a collector having a spiral side wall beginning adjacent the outlet of said vertical passage and having a portion occupying space above the outlet of vertical passage tube and nearer to the axis thereof than said outlet is, a direct discharge portion forming a down-stream continuation of the vertical passage outlet and adapted to decelerate the flow between upper and lower surfaces, and a lateral projection extending the full length of said discharge portion.
13. In a turbine, a draft tube having a radially spreading vertical passage provided with an outlet and a collector adapted to receive water from said vertical passage at a considerable velocity and to cause said water to be continuously decelerated, said collector occupying space above and within the radial limits of the outlet of said vertical passage, and having a spiral side wall beginning adjacent the outlet of said vertical passage, a direct discharge portion forming a down-stream continuation of the vertical passage outlet adapted to decelerate the flow between upper and lower surfaces.
14. In a turbine, a draft tube having a radially spreading vertical passage provided with an outlet and a collector adapted to receive water from said vertical passage at a considerable velocity and to cause said water to be continuously decelerated, said collector occupying space above and within the radial limits of the outlet of said vertical passage, and having a spiral side wall beginning adjacent the outlet of said vertical passage, a direct discharge portion forming a down-stream continuation of the vertical passage outlet adapted to decelerate the flow between upper and lower surfaces.
15. A draft tube having means for discharging water radially in substantially all directions, means for conducting the water discharged in one direction between flow surfaces which diverge by an angle not exceeding 20° , and means for collecting the water discharged in other directions and conducting it through a channel of increasing area whereby it is turned into the said one direction and its velocity diminished.
16. The combination in a draft tube comprising a radially spreading vertical passage provided with an outlet and a collector formed of two spiral passages which are arranged to receive water discharged from said vertical passage in substantially all directions except a general down-stream direction, said vertical passage having a wall projecting into said collector to form the outlet of said vertical passage, and said wall having a continuation in a down stream direction to form a roof of a passage to receive and conduct, toward the tail race, water discharged in a downstream direction from said vertical passage, said continuation having a portion extended radially with respect to the main body portion thereof and the outer edge of one portion having a curvature different from that of the outer surface of the other portion, and all of said passages gradually increasing in area at such rates that the velocity head of the flow entering said passage is efficiently converted into pressure head.
17. A draft tube for hydraulic turbines, comprising walls forming substantially vertical and horizontal passages, the wall of said vertical passage projecting into said horizontal passage and being turned so as to extend up and downstream, the dimension of said downstream projection being greater than that upstream and the body portion of said projecting wall and its downstream projection being so shaped as to lie entirely inside of a straight horizontal line contacting with any point of the side surfaces of said body portion, while the side surfaces of said downstream projection have vertical portions of material depth.
18. A draft tube for hydraulic turbines, comprising walls forming substantially vertical and horizontal passages, the wall of said vertical passage projecting into said horizontal passage and being turned so as to extend up and downstream, the dimension of said downstream projection being greater

than that upstream and the body portion of said projecting wall and its downstream projection being so shaped as to lie entirely inside of a straight horizontal line contacting 5 with any point of the side surfaces of said body portion, whereby said horizontal passage has two lateral passages which are disposed entirely above the floor of said horizontal passage.

10 19. A draft tube for hydraulic turbines, comprising walls forming substantially vertical and horizontal passages, the wall of said vertical passage projecting into said horizontal passage and being turned so as to extend up and downstream, the dimension of 15

said downstream projection being greater than that upstream and the body portion of said projecting wall and its downstream projection being so shaped as to lie entirely inside of a straight horizontal line contacting 20 with any point of the side surfaces of said body portion, whereby said horizontal passage has two lateral passages of greater depth than the passage beneath the said downstream projection and said lateral passages 25 being disposed substantially entirely above the flow of said passage beneath the downstream projection.

LEWIS FERRY MOODY.

CERTIFICATE OF CORRECTION.

Patent No. 1,713,775.

Granted May 21, 1929, to

LEWIS FERRY MOODY.

It is hereby certified that error appears in the printed specification of the above numbered patent requiring correction as follows: Page 6, line 27, claim 19, for the word "flow" read "floor"; and that the said Letters Patent should be read with this correction therein that the same may conform to the record of the case in the Patent Office.

Signed and sealed this 30th day of July, A. D. 1929.

(Seal)

M. J. Moore,
Acting Commissioner of Patents.
